HOUSE NUMBER PLATE

William E. Hellyar, Detroit, Mich.

Application July 22, 1954, Serial No. 31,547

Term of patent 7 years

(Cl. D1—7)

Fig. 1 is a front face view of a house number plate embodying my design.

Fig. 2 is a top edge view of the house number plate shown in Fig. 1.

The characteristic features of my design reside in the portions shown by means of full lines in the drawings.

I claim:

The ornamental design for a house number plate, substantially as shown and described.
